UNITED STATES PATENT OFFICE.

PALACE BUTLER, OF INDIANAPOLIS, INDIANA, ASSIGNOR OF ONE-HALF TO MARGARET M. MASON, OF INDIANAPOLIS, INDIANA.

WALL-PAPER PASTER, TRIMMER, AND FOLDER.

Application filed August 2, 1923. Serial No. 655,339.

To all whom it may concern:

Be it known that I, PALACE BUTLER, a citizen of the United States, residing at Indianapolis, in the county of Marion and State of Indiana, have invented new and useful Improvements in Wall-Paper Pasters, Trimmers, and Folders, of which the following is a specification.

The object of this invention is to provide a machine for applying paste to the proper surface of wall paper, trimming one or both edges of the paper and folding and piling it like it is usually folded and piled when pasted by hand for convenient handling in the operation of applying the pasted paper to a wall or ceiling.

A further object of the invention is to provide a machine capable of adjustment to paste and trim wall paper of varying widths fed into the machine from a roll, and to produce such a machine that is simple, convenient, compact, durable, efficient, and so readily portable that it may be easily carried from place to place wherever the handling of paper is to be carried on; that will not wrinkle, tear or crease the paper or smear paste upon the face or figured surface thereof.

I accomplish the above and many other minor objects which will hereinafter appear, by the mechanism illustrated in the accompanying drawings, in which—

Fig. 1, is an elevation of that side of the machine from which the pasted and trimmed paper discharges. Fig. 2, is an elevation of the crank-end of the machine, showing in dotted lines how the front section of the folded paper table may be folded upwardly and backwardly for the purpose of compacting the machine when it is to be carried around. Fig. 3, is an elevation looking at the opposite end from that shown in Fig. 2. Fig. 4 is a top plan view. Fig. 5, is a cross section of all but the legs, on the line 5—5 of Fig. 4. Fig. 6, is a detail in perspective of a portion of the table-track on which the pasted paper is folded and stacked, showing a hinged and folding end of said track. Fig. 7 is a side elevation of the plate that guides the universal shaft for moving the folding

table. Fig. 8, is a perspective view of the scraper for removing paste excess, the thickness of the blade being exaggerated to more clearly show its corrugations, and Fig. 9 is a perspective view of the device for measuring the lengths of strips to be cut off.

Like characters of reference indicate like parts in the several views of the drawings.

A relatively fixed base or table 10 supports the operative mechanism of my invention and for convenience the table is supported upon four folding legs 11. These are crossed in pairs as shown and the legs of each pair are pivoted together at their intersections. They are held in crossed relation to each other by a two-bar brace 12. The outer ends of the bars are pivoted to the respective legs and their inner ends are lapped and also pivoted together. A stop 13 on one allows the bars to break in one direction only. (See Figs. 2 and 3.)

The legs of each pair, sloping in the same direction, are connected by a two-piece bar 14, pivoted together at 15. A stop 16 on one allows the bars to break only in an upward direction for folding, and in use, this is prevented by a diagonal brace 17 attached at one end to pivot 15, and having a hook-slot at the other to hook over a pin 18 in one of the legs. By releasing the brace bars the bars and legs may be compactly folded for carrying from place to place.

Fixed to the top of table 10, are four standards 19, that support a paste-holding box 20, here shown as the segment of a cylinder. In its ends 21 oblique grooves 22 are formed to receive the end trunnions 23 of a cylinder 24. The lower portion of the cylinder is submerged in the paste and its function, when rotated, is to carry an excess of paste up and apply it to the wall paper. The grooves 22 allow for the easy removal of the cylinder when it and the interior of the paste-box are to be cleaned. The box 20 has a clean out opening closed while the machine is in use, by a screw-cap 25.

Closing the grooves 22, are angle-bars 26, retained by pins 27, one of which has a wing-nut 28, the removal of which allows the bars to be lifted off for cleansing purposes.

The vertical flanges of bars 26 support a rod 29, on which a U-shaped frame swings. The member connecting the stems of the frame is in two-lapped parts which pass through a 5 pair of loops 30, 30, and are held by a set-screw 31. This allows the frame to be adjusted in width to receive rolls of wall paper of different dimensions between the stems. The stems of the U-shaped frame support a 10 rod 32 on which the roll 33 of wall paper is mounted. The frame is adjustable as a whole, longitudinally of rod 29 by rotating the rod, a screw-threaded portion 34 of which, (see Fig. 4) passes through a nut 35 15 fixed to the frame. The rod 29 is rotated by a hand-wheel 36. A bar 37, much longer than the stems of the frame, is fixed to one of the stems to even the paper against, so the paper will feed through the machine 20 properly. The roll of paper bears by gravity against the paste supplying cylinder 24, the paper being unrolled and threaded through the machine as shown in Fig. 5. It passes from the cylinder 24 to and over a 25 roller 38, mounted on a shaft 39, the bearings for which are held closed and are released by the angle-bars 26. On an extended end of shaft 39 is a hand-crank 40, by which power is manually applied to operate the 30 machine. The shaft 39 is the master shaft from which all of the other operative parts are driven. A sprocket wheel 41 on shaft 39 is connected by a link-belt with a larger wheel 42 on a trunnion of cylinder 24.

35 Supported by suitable standards that are attached to the angle-bars 26, is a bar 43, here shown approximately ovoid in cross section, to the tapering side of which the ends of a pair of strap springs 44 are fastened. 40 These pass under and around the bar and terminate above the roller 38 with bifurcations in which circular cutters 45 are rotatably mounted.

45 A bolt 46 from the secured end of each spring 44, passes through the spring-body above it to a rocking cam 47, and by proper manipulation of the cam the spring may be released to raise the cutters away from the wall paper or compressed to bring them into 50 cutting contact. The cutters are adjustable longitudinally of the bar 43 on the latter by releasing their cams which loosens the spring so they can be slid to desired position on the bar. This adjustment is to cut 55 the edges of the wall paper at the right places.

60 The above described cam-adjustment of the cutters provides means for releasing one of the cutters when it is not desired to cut the edge of the paper on that side of the roll. The cams also afford individual cutting adjustment, but the principal cutting pressure is secured by an arm 85 hinged to the end of bar 43 to rock it, which arm is 65 held to a given position of the cutters by

an engagement with a toothed-rack 86, on the end of the paste-box.

Additional cutters may be used where it is desired to trim the margins and also to cut the piece into narrower strips, at one 70 operation.

The members 48, of the standards, supporting bar 43 are curved obliquely and so positioned as shown in Figs. 1, 2, 3 and 5, as to properly support the trunnions of 75 a roller 49 bearing by gravity against the printed face of the wall paper passing over the roller 38. The face of the roller may be plain, but it will preferably be corrugated spirally as shown in Fig. 1, to even the 80 paste on the pasted side of the wall paper passing between the roller 49 and the roller 38, and more particularly, to feed the paper through the machine. On the end of the shaft 39 opposite the hand crank 40, is 85 mounted a spur gear 51 having a diameter approximating that of the roller 38. The roller 49 has a spur gear 50 mounted on its end to mesh with the gear 51 and of a diameter considerably less than that of the 90 gear 51, such that in turning the roller 38, the roller 49 is thereby positively driven through the gears 51 and 50 at a speed greater than the speed of the roller 38. A scraper 52 is attached to the edge of the 95 paste-box below roller 39 to remove all excess of paste from the latter; but to leave a desired minimum on roller 39, I provide a series of corrugations or grooves 53 in the 100 contacting edge of the scraper, but these may be omitted. Metal clips 54 of S-shape are the attaching means between the paste-box and scraper and allow for easy removal of the scraper for cleaning it and the box. The scraper is separated from the box-edge 105 by the thickness of the clip material, which provides room for the return to the box of the paste excess removed by the scraper.

The pasted paper has now to be folded and stacked for convenient handling by the 110 paper hanger, and to accomplish this I allow it to drop from roller 39 upon a platform 55 below, having a reciprocating travel, and to keep the pasted side of the paper from adhering to the side of the 115 paste-box as it passes, I form the ribs 56' (see Fig. 1) on the side of the box.

The platform 55 has underside battens 56 with plates 57 attached to their undersides and projecting outwardly and laterally. 120

The plates slide on metal tracks 58, having flanges 59 turned over the extended edges of plates 57 to prevent derailing of the platform.

125 Supported by a hanger 60 from the middle of the track is a rack-bar 61 with cylindrical teeth which are engaged by a pinion 62 mounted on the end of a shaft 63 which is connected by a universal joint 64 (see Fig. 1) with a stationary shaft 65 bear- 130

ing a sprocket-wheel 66 that is driven by a link-belt 67 from a wheel 76 on the master shaft 39.

By the above construction the shaft 63 and its pinion 62 have freedom of movement that permits the pinion to pass from one side of the rack to the other when it reaches an end of the rack, and thereby reverse the direction of travel of the rack and consequently of the paper folding platform to which it is attached. Movement of shaft 63 is limited by a suitable cam-opening 68 in a fixed plate 69, and the return of the table by the pinion passing around the ends of the rack is insured by suitable stops, such as the block 70 at one end and a bar or finger 71 at the other which finger contacts with the downwardly bent end of a plate 72. The plate 72 is pivoted to the platform and its bent end projects down through a curved slot in the table which slot is long enough to allow the plate and its bent end to swing out of the path of finger 71, when removal of the platform from the machine is desired.

It is necessary often to change the position of the platform relative to the pasted paper coming to it, and this is accomplished by disengaging a dog 74, carried by the shaft 39, from a toothed-wheel 75 on the hub of sprocket-wheel 76. When the dog is out of engagement with wheel 75, the platform drive mechanism is released, and the platform can be moved to any required position and connected up again by re-engaging the dog.

For very wide paper the platform is widened by plate extensions 90, having clamp plates 91 to engage the edge of the platform.

The track for the support of the reciprocating platform is made longer than the width of the paste-box above, by hinged bracket extensions 92. These have lower diagonal brace members 93 which, with the track portion above, are hinged to the ends of the main tracks and fixed brackets 94, by vertical pins 95. The hinge openings through members 93 are slotted longitudinally for a swinging movement of the bracket vertically to seat and unseat a locking-lug of the end of the brace, in a hole in bracket 94. The above construction permits of the folding of brackets 92.

I have next to describe a means for measuring the lengths of wall paper strips, and for stopping the machine when the length it has been set for is measured.

A shaft 78 has a loose wheel 79 driven by a worm on a shaft 89, on which is a sprocket-wheel that is driven by a link belt 81 from a wheel on the shaft 39. The wheel 79 has a radially notched hub 81 with a notch of which a dog pivoted to shaft 78, is engaged.

A horizontal arm 83, of the dog acts in the dual capacity of a pointer and also as a stop, with a dial-ring 84 fixed concentrically of shaft 78. The upper face of the dial-ring is suitably graduated, as in feet, 70 and an adjustable stop 85 is fixed to it with which the arm 93 contacts and locks the machine when the arm reaches the stop. The operator then cuts off the pasted and trimmed strip with his shears, raises the arm until it passes the stop in the further operation of the machine, and dropping the arm again to horizontal position, continues the pasting and trimming of another strip.

While I have illustrated and described 80 my invention with more or less minuteness, it is capable of many modifications without departing from the spirit of the invention, and I therefore do not desire to be held strictly to the construction shown and de- 85 scribed nor any more than is required by the appended claims.

I claim:—

1. In a device of the kind described, the combination of a paste receptacle, a paste 90 cylinder partially submerged in the paste in said receptacle, a paper-roll carrier adjustable in width and also transversely of the paste receptacle, from which carrier the unrolled paper passes over the paste 95 cylinder, a paste removing roller in the receptacle in proximity to the paste cylinder over which roller the paper passes, a paste distributing and paper feeding roller pressing the pasted paper against the paste removing 100 roller, and means for removing the paste excess from said paste removing roller.

2. In a paper pasting and trimming machine in combination, a paste applying cylinder over which the paper passes, a 105 paste removing roller over which the paper passes from said cylinder, a gravity presser feed-roll above the paste removing roller between which and said paste removing roller the pasted paper passes, a rock-shaft 110 substantially ovoid in cross section, a paper cutting knife, a holder for the knife having a spring member crossing over and then downwardly and under and fastened to the tapering side of the shaft, a bolt secured at 115 the tapering side of the shaft and passing through the overlying portion of the holder, and a cam pivoted to the upper end of the in said receptacle, a paper-roll carrier ad- 120 bolt and contacting the holder to clamp the holder to the shaft.

3. The combination, with a paste removing roller over which a paste-coated paper passes, of a positively driven feed-roll being carried by projecting trunnions free to roll 125 on inclined guides, said feed-roll rolling down said guides by gravity and thereby pressing the paper against the roller and a substantially opposite scraper-knife removing an excess of paste from the roller. 130

4. In a paper pasting and trimming machine, a paste applying cylinder over which the paper passes, a paste removing roller over which the paper passes from said cylinder, a gravity presser feed-roll above the paste removing roller between which and said paste removing roller the pasted paper passes, and means for guiding the roll toward the roller.
10. 5. In a paper pasting and trimming machine, a paste applying cylinder over which the paper passes, a paste removing roller over which the paper passes from said cylinder, a gravity pressure feed-roll above the paste removing roller between which and said paste removing roller the pasted paper passes, and means for guiding the roll toward the roller, comprising trunnions on the ends of the roll and guides contacted by the trunnions.
20. 6. In a paper pasting and trimming machine in which the paper is fed through from a roll, means for applying the paste to the paper, means for removing the excess of paste, and for positively moving the paper past said other means, and dial means for measuring the unrolled and pasted paper into shorter lengths for hanging.
30. 7. In a paper pasting and trimming machine in which the paper is fed through from a roll, means for applying the paste to the paper, means for removing the excess of paste, means for positively moving the paper past said other means, and means for measuring the pasted paper into shorter lengths for hanging, and automatic means for stopping the operation of the pasting machine when the measurement of each length is completed.
40. 8. In a paper pasting and folding machine, means for applying regulated quantities of paste to the paper as the paper is fed through the machine from a roll; a reciprocating platform upon which the pasted paper is deposited and folded by the travel of the table, means connected and synchronized with the pasting means for actuating the platform, and means for disconnecting the platform actuating means for manual timing adjustment of the platform travel with the pasting operations.
50. 9. In a paper pasting and folding machine, means for applying paste in regulated quantities to the paper fed through the machine, comprising a power shaft on which a paste excess removing roller is mounted and from which shaft the other operative parts are timed, in combination with a platform receiving the pasted paper and having a reciprocating travel to fold and stack the paper, means for reciprocating the platform including power transmission means driven from said shaft, and means for disconnecting said last means from the shaft for the manual timing adjustment of the platform
- travel to make the paper fold properly thereon.
10. 10. In a paper pasting, trimming, and folding machine, means for applying paste in regulated quantities to paper coming through the machine from a roll, in combination with a platform on which the pasted paper is deposited, folded, and stacked by a reciprocating travel of the platform, and mean for reciprocating the platform, comprising a track to guide it, a toothed-rack secured to the platform, a rotating pinion driving the rack and passing from one side of the rack to the other at the ends of the rack to change the direction of movement of the rack.
15. 11. In a paper pasting, trimming, and folding machine, means for applying paste in regulated quantities to paper coming through the machine from a roll, in combination with a platform on which the pasted paper is deposited, folded, and stacked by a reciprocating travel of the platform, and means for reciprocating the platform, comprising a track to guide it, a toothed-rack secured to the platform, a rotating pinion driving the rack and passing from one side of the rack to the other at the ends of the rack to change the direction of movement of the rack.
20. 12. In a paper pasting, trimming, and folding machine, means for applying paste in regulated quantities to paper coming through the machine from a roll, in combination with a platform on which the pasted paper is deposited, folded, and stacked by a reciprocating travel of the platform, and means for reciprocating the platform comprising a track to guide it, a toothed-rack secured to the platform, a rotating pinion driving the rack and passing from one side of the rack to the other at the ends of the rack to change the direction of movement of the rack, a shaft on one end of which the pinion is mounted, a rotating shaft, a universal joint connecting the two shafts, and means for limiting the lateral movement of the pinion carrying shaft.
25. 13. In a paper pasting, trimming, and folding machine, means for applying paste in regulated quantities to paper coming through the machine from a roll, in combination with a platform on which the pasted paper is deposited, folded, and stacked by a reciprocating travel of the platform, and means for reciprocating the platform comprising a track to guide it, a toothed-rack secured to the platform, a rotating pinion driving the rack and passing from one side of the rack to the other at the ends of the rack to change the direction of movement of the rack, a shaft on one end of which the pinion is mounted, a rotating shaft, a universal joint connecting the two shafts, and means for limiting the lateral movement of the pinion carrying shaft, comprising a member having a cam-opening through which the pinion carrying shaft passes.
30. 14. In a paper pasting, trimming, and folding machine, means for applying paste in regulated quantities to paper fed through the machine from a roll of paper, in combination with a platform on which the pasted paper is deposited, folded, and stacked by a reciprocating travel of the platform, means for reciprocating the platform comprising a track to guide it, a toothed-rack secured to the platform, a rotating pinion driving the rack and adapted to pass from one side of

the rack to the other at the ends of the rack to change the direction of movement of the rack, and stop means adjacent each end of travel of the rack to hold the pinion in mesh with the rack and cause it to change to the other side of the rack by the continued rotation of the pinion.

14. In a machine for the purposes specified, means for applying paste to paper fed 10 from a roll through the machine, a recipro-

cating platform upon which the pasted paper is deposited and folded by the travel of the platform, and a track, exceeding the dimensions of the rest of the machine, on which the platform travels, said track being 15 in hinged members that may be folded to reduce the dimensions of the machine.

Signed at Indianapolis, Indiana, this the 19th day of July, 1923.

PALACE BUTLER. 20
